(57) **CLAIM**

The ornamental design for a swimwear, as shown.

DESCRIPTION

FIG. 1 is a front view of an embodiment of swimwear, in accordance with the present invention;

FIG. 2 is a perspective view of the swimwear of FIG. 1; FIG. 3 is a left side view of the swimwear of FIG. 1; FIG. 4 is a rear view of the swimwear of FIG. 1;

FIG. 5 is a perspective view of the swimwear of FIG. 1; FIG. 6 is a perspective view of the swimwear of FIG. 1; and, FIG. 7 is a right side view of the swimwear of FIG. 1. The broken lines and the portions within the mannequin are for the purpose of illustrating environmental structure and form no part of the claimed design.

1 Claim, 7 Drawing Sheets
